UNITED STATES PATENT OFFICE

BENJAMIN F. HAYDEN, OF ST. LOUIS, MISSOURI, ASSIGNOR TO THE BYLAND REALTY & CONSTRUCTION COMPANY, INC., OF CINCINNATI, OHIO, A CORPORATION OF OHIO

BRICK-MAKING MACHINERY

Application filed November 14, 1927. Serial No. 233,135.

My invention relates to brick making machinery.

It is the object of my invention to provide a machine for making brick, preferably of material having a substantial portion thereof of cement.

It is my object to provide a machine that will produce air-dried brick as distinguished from those that are primarily baked.

10 It is my object to provide a machine in which the weight of the parts will so form and consolidate the material being used that the surplus moisture will be expelled from the mixture, the proper shape and density 15 will be accomplished and the quick drying of the article will be facilitated so that it will occupy the minimum of time in the process of production.

It is a further object to provide positive 20 means for maintaining the mould in elevated position. It is an object to provide means of uniformly distributing and delivering the material to be moulded to the forms.

Referring to the drawings:

25 Figure 1 is a front elevation of my machine. Figure 2 is a side elevation thereof, showing the mould in lowered position.

Figure 3 is a side elevation showing the mould in elevated position.

30 Figure 4 is a top plan view of the charging hopper.

Figure 5 is a section on the line 5—5 of Figure 4.

Figure 6 is a right-hand elevation of the 35 upper portion of the frame and supporting bracket.

Figure 7 is a detail of the upper part of the mechanism from the front thereof, showing the arrangement of the links.

40 Figure 8 is a top plan view of the link mechanism.

Figure 9 is an end elevation showing the belt shifting and driving mechanism for the charging hopper.

45 Figure 10 is a bottom plan view of the hopper car actuating mechanism with the car and its racks removed for the purpose of illustration.

Figure 11 is a side elevation of the brake 50 to prevent overrun of the drum and rewind-

ing of the chain when the tamper descends.

Referring to the drawings in detail, 1, 2, 3 and 4 designate four upright corner frame members which are connected at the bottom by fore and aft connecting members 5 and 6, 55 and at the top by fore and aft members 7 and 8.

Intermediate of these frame members there is located a transverse platform 9, which serves as the pallette support. 60

The lower ends of the frame members are connected together by a transverse rod 10. This rod 10 is connected to the side members 5 and 6. The upper ends of the frame members are connected together by the transverse 65 rods 11 and 12.

Within the corner frame members, intermediate thereof on either side thereof, there are located vertical guide rods 13. These 70 guide rods are positioned in the platform 9 in the sleeves 14. The mould frame 15 is guided on the rods through the sleeve 16. The tamper frame 17, carrying the tampers 18, is also guided on these rods through the sleeve 19. The upper end of the rod terminates in either 75 the side members 7 or 8. On the side members 7 and 8 there is mounted a power shaft 20 carrying a cam 21, which is adapted to engage with the roller 22 pivotally mounted on the segmental rack 23, whose teeth 24 engage 80 with the corresponding teeth 25 of a similar segmental rack 26.

These racks are pivoted on the rods 11 and 12 and are elevated with the cam 21 engaging the roller 22. Each rack is connected to an 85 adjustable link 27, the lower end of which is connected pivotally to the mould frame 15. Thus the elevation of the racks results in the elevation of the mould frame. When the mould frame is so elevated and it is desired to maintain it in elevated position the supporting cam member 28, having a shoulder 29, is moved by its handle 30 and a spring 31, which is connected to one of the frame members, so that the shoulder 29 is beneath the sleeve 16, as in Figure 3. This permits of the withdrawal on the pallette 32 of the moulded products. 95

When the mould frame is in lowered position over the pallette and it is desired to load 100

the mould frame with suitable plastic material for moulding, then the hopper car 33, having a supply trough 34, is moved over the frame 15 on its wheels 35 traveling on the tracks 36. The rear axle 37 serves as a driving axle for a drum 38 within the hopper, which actuates a belt 39 forming a moving bottom for the supply trough 34. The other end of the belt passes over the roller 40, pivotally mounted upon the stub shaft 41. This causes the material to be fed beneath the movable end wall 42 of the supply trough into the open-bottomed area 43, where it engages the moving impeller 44 adjacent the stationary front wall 45 of the hopper. The material passes out through the open bottom 46 into the mould frame 15. The impeller 44 is mounted on the axle 47 of the forward wheels. The hopper itself is moved bodily by means of the rack 48 carried on the side thereof, which is engaged by the pinion 49 driven by the shaft 50 carried in the bracket 51 to meet the track 36.

The forward wall 42 of the supply trough is adapted to be moved to open position through the lever 52 and the spring 53. This forward wall 42 is pivoted at 54 on the side walls of the hopper car.

Referring to Figure 10, there will be seen the top plan view of the actuating mechanism for moving the hopper car into and out of charging position. The shaft 50 is driven by the pulleys 55 at either end thereof. These pulleys are provided with clutch arms 55^a engaging the clutch drum 56, which is slidably mounted upon the shaft 50. The lever 57, which is pivoted upon the bracket 58, is pivotally connected to the link 59. Its other end is pivotally connected to a second lever 60 carrying a second clutch sleeve 61 for engagement or disengagement with the clutch arm 62 of the second pulley 63. This lever 60 is pivoted upon the second bracket 64. Thus the movement of the lever 57 will clutch or declutch the shaft 50 to the alternate pulleys for alternate movement of the charging box forward or backward, as the movement in one direction would cause one clutch to engage and the movement in the other direction cause the other clutch to engage, and the first-mentioned clutch to be disengaged.

The tamper members 18 are in any desired configuration for forming bricks of the desired shape. They are suspended from a very heavy block 17. This block is moved upwardly by power and allowed to drop by gravity. The power elevation means consists of a chain 65, which is wound on a drum 66. This drum is connected by a clutch 67 to a clutch face 68 of the actuating shaft 20. This shaft is driven by a suitable pulley 70.

In order to hold the tamper in its elevated position, I provide a pair of swinging supports 71 and 72, which are mounted upon the brackets 73 and 74 that are in turn pivoted

on the vertical pivot rods 75 carried in the lower bracket 76 and upper fore and aft members 7 and 8.

The brackets 71 and 72 have each connected thereto an interconnecting spring 77 to maintain them in inner tamper supporting position.

These brackets are swung outwardly with their supports by the links 78 and 79, which are pivoted thereto. These links are connected to an angular lever 80, pivoted at 81 to the transverse member 82 between the frame members and having a handle 83. When the operator pulls the handle towards himself he moves the supports 71 and 72 from out of engagement with the tamper, allowing it to drop. This movement is against the resistance movement of the spring 77.

Method of operation

In operating the machine, assuming the parts to be as shown in Figure 1, the mould 15 is empty and rests upon the removable platen 32, which in turn rests upon the foundation 9. The power shaft 20 is rotating.

The operator moves the lever 57 in such a manner as to close the clutch 62, which results in moving the hopper forwardly over the mould. This forward movement permits of the movable front wall of the hopper 42 being moved about the pivot 54, due to the influence of the spring 53, as the restraining influence of the stop bracket 53^a has been removed.

The movement of the bottom 46 of the storage compartment of the hopper moves the plastic material into the discharge compartment 43, where it is engaged by the impeller 44. When the hopper is moved forward and dumps its contents it is returned to its initial position and the belt 39 is reversed in its movement, thereby stopping the discharge. This return is effected by disengaging the clutch 62 and engaging the clutch 55.

Upon the accomplishment of the loading of the mould the lever 80 is pulled so that the tamper 18 may drop.

The tamper is elevated by causing the clutch 67 and 68, through the lever 68^a, to be engaged with the shaft 20 which serves to elevate the tamper through the chain 65 being wound on the drum 66, which is mounted on the shaft 20. When the tamper has been elevated the clutch can be disconnected as the spring pressed supporting arms or brackets 72 and 73 will be moved by the spring 77 into engaging position.

It then becomes necessary to elevate the mould 15, and this is done by moving the lever 21^a so that the cam 21 carried on the shaft 20 will be moved laterally into position to engage with the roller 22 against the resistance of the spring 21^b. The cam engaging with the roller actuates the racks 23 and 26, which interengage through the teeth 24 and 130

25, thereby moving the mould upwardly through the agency of the rods 27, while the tamper holds the molded product on the platen. Upon the movement to its uppermost position the stop 28 moves beneath the sleeve 16, holding the mould in elevated position. The lever 21^a can be released and the spring 21^b will move the cam 21 into inoperative position.

10 The platen 32 can then be withdrawn with the moulded products resting upon it.

A brake for the rewinding mechanism is provided consisting of a brake arm 84 hung on the transverse rod 85 on hooks 86. These rods are connected between the frame members. A shoe 87 is provided with a brake lining 88 which engages with the clutch drum 89 preventing the chain from rewinding if there is a sudden descent in return movement 20 of the tamper.

I desire to comprehend within my invention such modifications as may be clearly embraced within my claims and the scope of my invention.

25 I claim:

1. In a brick machine, a frame, a platen foundation, a platen, a movable mould, a movable tamper and means including a pair of cam-operated segmental racks to move said mould vertically equally in all parts thereof, and means adapted to maintain said mould in elevated position when so elevated.

2. In a brick machine, a guiding frame, a platen, a mould adapted to rest on the platen, a power means continuously operating, means including a pair of cam-operated segmental racks to elevate said mould adapted to be driven by said power means, means to connect said elevating means to said power means, a tamper, means to elevate said tamper connected to said power means, said mould elevating means being adapted to move said mould equidistantly in all parts thereof.

3. In a brick machine, a guiding frame, a platen, a mould adapted to rest on the platen, a power means continuously operating, means including a pair of cam-operated segmental racks to elevate said mould adapted to be driven by said power means, means to connect said elevating means to said power means, a tamper, means to elevate said tamper connected to said power means, said mould elevating means being adapted to move said mould equidistantly in all parts thereof, and means adapted to be moved into position beneath said mould means upon being elevated to maintain it in elevated position after the elevating means has ceased to operate.

4. In a brick machine, a guiding frame, a platen, a mould adapted to rest on the platen, a power means continuously operating, means including a pair of cam-operated segmental racks to elevate said mould adapted to be driven by said power means, means to connect said elevating means to said power means,

a tamper, means to elevate said tamper connected to said power means, said mould elevating means being adapted to move said mould equidistantly in all parts thereof, means adapted to be moved into position beneath said mould means upon being elevated to maintain it in elevated position after the elevating means has ceased to operate, and means to maintain said tamper in elevated position after said tamper elevating means has ceased to operate.

5. In a brick machine, a frame, a platen support, a platen, a mould adapted to rest thereon, a tamper adapted to be inserted in said mould guiding members for said mould and said tamper, a continuously rotating power shaft, means to intermittently connect said power shaft to said tamper to elevate it, means to elevate said mould, means to intermittently connect said power shaft to said mould elevating means, means yieldingly moved into position to maintain said mould in elevated position, means yieldingly moved to maintain said tamper in elevated position, and manual means for removing said last-mentioned means to inoperative position to permit of the descent of the mould and the tamper.

6. In a brick machine, a frame, a platen foundation mounted therein, a removable platen mounted thereon, a mould adapted to rest on said platen, guide rods on either side of said mould adapted to guide it in a vertical movement, a tamper adapted to be moved within said mould guided by said guides, a power shaft, a cam on said power shaft, arms carrying interlocking segments mounted on said frame, means connecting said segments to the four corners of said mould, a roller on one of said segments adapted to engage with said cam, and means for moving said cam into engagement with said roller whereby the rotation of the cam by the power shaft will elevate the mould.

7. In a brick machine, a frame, a platen foundation mounted therein, a removable platen mounted thereon, a mould adapted to rest on said platen, guide rods on either side of said mould adapted to guide it in a vertical movement, a tamper adapted to be moved within said mould guided by said guides, a power shaft, a cam on said power shaft, arms carrying interlocking segments mounted on said frame, means connecting said segments to the four corners of said mould, a roller on one of said segments adapted to engage with said cam, means for moving said cam into engagement with said roller whereby the rotation of the cam by the power shaft will elevate the mould, said mould being guided on the guides by lateral extending eyes, a cam-shaped stop yieldingly engaging one of said eyes having a shoulder on said stop for engaging with the under surface of said eye whereby when the mould is elevated the cam-

shaped stop will be moved beneath the eye to maintain the mould in elevated position, and means on said stop for moving it into inoperative position to permit the mould to drop.

5 8. In a brick machine, vertically arranged supporting framework connected together by transverse members, a platen platform mounted in said framework, a detachable platen slidably mounted thereon, a mould 10 mounted on said platen, means for elevating said mould, a tamper, means for elevating said tamper, guide rods for said mould and said tamper, said tamper engaging with said guide rods through projecting eyes, side arms 15 pivotally mounted on said frame members, adapted to engage beneath the eyes of said tamper to maintain the tamper in elevated position, yielding means to maintain said side arms in engaging position, link mechanism 20 adapted to move said arms into disengaging position and a lever in said link mechanism for operating it.

9. In a brick machine, spaced side frame members connected at the top and bottom fore 25 and aft thereof by connecting members, transverse rods connecting said side frame members, guide rods carried on said side frame members, a tamper guided on said guiding rods, brackets pivoted on said side frame 30 members adapted to swing into engagement with said guiding rods beneath said tamper, yielding means to maintain said brackets in engaging position with the tamper, links connected to said swinging brackets, a lever connected to said links, and means to elevate said tamper whereby when the tamper is elevated 35 said supporting swinging brackets move into engaging position and when actuated by said lever are moved to disengaging position.

40 10. In a brick machine a frame, a mould guided therein, a platen, a tamper guided therein, a common power means for elevating said tamper and said platen, a loading hopper, means driven from said common power 45 means for moving said loading hopper over said mould and back to its initial position, said hopper being divided into a storage compartment and a delivery compartment, means to move material from said storage compartment to the delivery compartment in the 50 hopper, means to actuate said delivery means when the hopper is moved to delivery position.

55 11. In a brick machine a frame, a mould guided therein, a platen, a tamper guided therein, a common power means for elevating said tamper and said platen, a loading hopper, means driven from said common power 60 means for moving said loading hopper over said mould and back to its initial position, said hopper being divided into a storage compartment and a delivery compartment, means to move material from said storage compartment to the delivery compartment in the 65 hopper, means to actuate said delivery

means when the hopper is moved to delivery position, and an agitator in said delivery chamber of the hopper.

12. In a brick machine a frame, a movable mould, a tamper power means including a cam-shaft and a pair of cam-operated segmental racks for elevating said tamper and said mould, a movable charging hopper adapted to be actuated by said common power means, means associated with said hopper for delivering the material therefrom adapted to be actuated when said hopper is moved. 70 75

13. In a brick machine a frame, a movable mould, a tamper power means for elevating said tamper and said mould, a movable charging hopper adapted to be actuated by said common power means, means associated with said hopper for delivering the material therefrom adapted to be actuated when said hopper is moved, said hopper being divided into a storage compartment and a delivery compartment, a movable wall between said compartments, means for moving said wall when the hopper is moved to delivery position. 80 85

14. In a brick machine a frame, a movable mould, a tamper power means for elevating said tamper and said mould, a movable charging hopper adapted to be actuated by said common power means, means associated with said hopper for delivering the material 90 95 therefrom adapted to be actuated when said hopper is moved, said hopper being divided into a storage compartment and a delivery compartment, a movable wall between said compartments, means for moving said wall when the hopper is moved to delivery position, a movable bottom for the storage compartment adapted to convey material beneath the movable wall into the discharge 100 compartment. 105

15. In a brick machine a frame, a movable mould, a tamper power means for elevating said tamper and said mould, a movable charging hopper adapted to be actuated by said common power means, means associated with said hopper for delivering the material 110 115 therefrom adapted to be actuated when said hopper is moved, said hopper being divided into a storage compartment and a delivery compartment, a movable wall between said compartments, means for moving said wall when the hopper is moved to delivery position, a movable bottom for the storage compartment adapted to convey material beneath the movable wall into the discharge compartment, and an impeller in the discharge 120 compartment for ejecting the material delivered to it from the storage compartment. 125

16. In a brick machine a frame, a platen support therein, a platen, a movable mould, a movable tamper, a charging hopper, a track supporting said charging hopper, a rack on said hopper, gears engaging the said rack, a common power means adapted to drive said gears and elevate said tamper and mould, 130

means for connecting said power to said hopper, tamper and mould respectively to actuate them, wheels supporting said hopper on said track, means connected to said wheels for ejecting material from said hopper when the hopper is moved, a storage compartment having a movable bottom in said hopper, a movable retaining wall in said hopper, an ejection compartment having an open bottom, means connected to said movable wall to actuate it mounted on said hopper, yielding means to move said movable wall into open position, and stationary retaining means to maintain said wall in closed position carried by the frame of the machine whereby when the hopper is moved to discharging position the movable bottom of the storage compartment moves the material into the discharge compartment beneath the movable wall, which has been yieldingly moved to open position.

17. In a brick machine a frame, a platen support therein, a platen, a movable mould, a movable tamper, a charging hopper, a track supporting said charging hopper, a rack on said hopper, gears engaging the said rack, a common power means adapted to drive said gears and elevate said tamper and mould, means for connecting said power to said hopper, tamper and mould respectively to actuate them, wheels supporting said hopper on said track, means connected to said wheels for ejecting material from said hopper when the hopper is moved, a storage compartment having a movable bottom in said hopper, a movable retaining wall in said hopper, an ejection compartment having an open bottom, means connected to said movable wall to actuate it mounted on said hopper, yielding means to move said movable wall into open position, stationary retaining means to maintain said wall in closed position carried by the frame of the machine whereby when the hopper is moved to discharging position the movable bottom of the storage compartment moves the material into the discharge compartment beneath the movable wall, which has been yieldingly moved to open position, and an impeller in said discharge compartment connected to said walls.

In testimony whereof, I affix my signature.

BENJAMIN F. HAYDEN.
